UNITED STATES PATENT OFFICE

168,425

AUTOMOBILE SAFETY DOOR LOCK

Joseph M. Schumann, Inglewood, Calif.

Application July 12, 1952, Serial No. 20,580

Term of patent 14 years

(Cl. D50—7)

To all whom it may concern:

Be it known that I, Joseph M. Schumann, a citizen of the United States and resident of Inglewood, in the county of Los Angeles and State of California, have invented a new, original, and ornamental Design for an Automobile Safety Door Lock, of which the following is a specification, reference being had to the accompanying drawing, forming a part thereof:

Figure 1 is a front elevational view of an automobile safety door lock, with the lock member in unlocked position, showing my new design;

Figure 2 is a bottom plan view thereof, with the lock member in locked position;

Figure 3 is a top plan view thereof, with the lock member in locked position; and

Figure 4 is a rear elevational view thereof, with the lock member in locked position.

I claim:

The ornamental design for an automobile safety door lock, substantially as shown.

JOSEPH M. SCHUMANN.
